UNITED STATES PATENT OFFICE.

GEORGE F. NAAB, OF LAKewood, AND HENRY PRELL, OF EAST CLEVELAND, OHIO,
ASSIGNORS TO THE NAAB MANUFACTURING COMPANY, OF CLEVELAND, OHIO,
A CORPORATION OF OHIO.

BLOWPIPE.

1,317,638.

Specification of Letters Patent. Patented Sept. 30, 1919.

Application filed April 27, 1917. Serial No. 164,953.

To all whom it may concern:

Be it known that we, GEORGE F. NAAB and HENRY PRELL, citizens of the United States, residing at Lakewood and East Cleveland, respectively, in the county of Cuyahoga and State of Ohio, have invented certain new and useful Improvements in Blowpipes, of which the following is a specification.

This invention relates to blow pipes or pressure burners, such as are used for producing a flame of high temperature for welding, brazing or like operations.

The object of the invention is to provide a simple construction of this kind which enables a very high temperature to be secured at low cost for fuel; which is convenient to manipulate and is capable of careful regulation as to the temperature and kind of flame produced; and which device is of simple construction and is not likely to get out of order in service.

A further object of the invention is to provide a blow pipe including a pressure producing device to which the air and gaseous fuel are supplied, said device being capable of not only forcing the fuel and air mixture to the burner, but of also mixing the fuel and air to promote combustion, and which blow pipe also includes a burner supplied by the pressure producing device and in which the mixture of fuel and air is still further diluted by an additional air supply.

Further objects of the invention are in part obvious and in part will appear more in detail hereinafter.

In the drawings, Figure 1 represents a side elevation of one form of device embodying the invention; Fig. 2 is a side elevation, on a larger scale, of the blower casing, the blower and motor being omitted; Fig. 3 is a sectional elevation, on the line 3—3 Fig. 2, and indicating the fan and a portion of the fan driving motor; and Fig. 4 is a central longitudinal section through the burner.

The blow pipe shown in the drawings comprises a suitable pressure producing device 1 to which the air and gaseous fuel are supplied, and which discharges the mixture to a connected tube or conduit 2 which conducts it to the burner 3. These parts may be of any suitable construction for the purpose.

The pressure producing device 1 comprises a hollow casing 4 having a lateral hollow ex-

tension 5 to the outer end of which is connected the tube 2. Said tube may either be threaded to the casing or may be merely inserted into an opening therein and clamped in position by a set screw 6, as shown.

The opposite end of the casing is circular to form an inner annular fan chamber 7 one side wall of which is provided with a large opening 8. The opposite wall of said chamber extends outwardly in the form of a hollow circular boss 9 whose outer wall is provided with a number of circumferentially spaced openings 11, and whose central portion is threaded to receive a screw 12 passing through a rotatably adjustable valve member 13 in the form of a disk or plate 70 having a series of openings 14 to coöperate with the openings 11. Said plate 13 is seated in a circular recess or depression 15 in the wall 10 and its central portion is extended outwardly in the form of a cap 16 75 in which is located the head of the screw 12. Preferably a light spring 17 is located between the head of the screw and the plate 13 to hold it yieldingly to its seat. The space within the lateral extension 9 communicates with a passage 18 in a hollow boss or enlargement 19 of the casing, and which is threaded at its outer end to receive a pipe or conduit 20 communicating with a source of gaseous fuel. Said boss or extension, if desired, may also be provided with a small side port 21 open to the atmosphere for preliminarily mixing with the fuel before it enters the fan chamber a small supply of air, although this is not essential. 90

The wall of the casing, opposite the valve member 13, forms a support for the motor and the pressure producing device operated thereby. As shown, 22 indicates a portion of the motor frame, which is attached by bolts 23 to the wall of the casing around the edges of the large opening therein. 24 indicates a portion of the motor, which may be of any suitable form, and is shown as an electric motor having a shaft 25 passing through an opening in the frame member 22. On its inner end the shaft 25 supports a suitable centrifugal fan member, shown as a body portion 26 held to the shaft 25 by a set screw 27 and having two or more radially extending vanes 28 which rotate in the annular chamber 7.

When the motor is started the fan sets up

suction in the chamber and draws in air through the ports 14, 11 and 21, and gas from the supply pipe 20. The air supply through the ports 14, 11 may be more or less restricted by turning the valve plate 13, while the gas supply through the pipe 20 may also be restricted by more or less closing the valve 29, in said pipe. The fuel is mixed with a preliminary air supply at the 10 port 21, is mixed with an additional air supply in the mixing-chamber in the hollow boss 9, and the mixture is made thoroughly homogeneous in the fan chamber. The product is discharged into the tube 2, through 15 which it passes to the burner to be described.

The burner comprises a casing member 30 suitably attached to the tube 2, either threaded thereon or merely sleeved over the same and held adjustable thereon by the set screw 31, as shown. Intermediate its ends said casing member is enlarged to form a hollow chamber 32 surrounding the end of the tube. In said chamber is a baffle plate 33, shown as a circular plate against which the stream 25 of mixture impinges so that it is forced to travel outwardly and around the edges of said plate. This baffle plate may be supported in any desired manner, such as by being attached to the casing 30, but as shown, it 30 is attached to the central portion of a spider member 34 mounted in the tube 2. Said spider member is provided with several large openings 35 between its radial vanes to permit the free flow of mixture and may 35 either be threaded into the tube or a driving fit therein, as shown.

Beyond the chamber 32 the casing 30 is provided with a cross wall 36 having a central opening 37 therein in advance of the 40 baffle plate. After the mixture passes around the edge of the baffle plate it travels inwardly toward the central axis and through the opening 37. Beyond the wall 36 the outer wall of the casing diverges outwardly, as at 38, and is provided with a series of circumferentially spaced ports or 45 openings 39, whose axes converge toward the front end of the burner. The advancing stream of mixture produces a suction effect 50 at the inner ends of the ports 39, so that additional air is drawn in through said openings and is supplied to and mixed with the mixture, which flows through the forward nozzle end 40 of the burner and issues from 55 the opening thereof, where it burns as a hot flame.

The flow of mixture through the burner may be more or less advanced or retarded by slight adjustment of the casing 30 on the 60 tube 2, to adjust the space between the baffle 33 and wall 36.

Suitable means may also be provided for supporting the blow pipe. As shown, the casing 4 is provided at one point with a split 65 clamping ear 41 to receive a supporting rod

or post 42 to which the device may be clamped by turning up the clamping screw 43.

The blow pipe described is of simple construction and its various adjustments permit of exact regulation of the size and temperature of the flame, due to the capability of more or less restricting or promoting the flow of air or fuel, or both, and the possibility of regulating the proportions of air 75 and fuel to secure perfect combustion. The admission of both air and fuel to the chamber of the pressure producing device also secures a very intimate mixture and promotes combustion. 80

What is claimed is:—

1. In a blow pipe, a tube, means for supplying a mixture of air and fuel to said tube, and a burner carried by said tube and comprising a casing member, a nozzle end therefor having an opening therein of substantially uniform diameter, and a transverse wall within the nozzle end and provided with a centrally disposed mixture discharge opening of less diameter than the opening in said nozzle end whereby a suction is created within said nozzle end. 85

2. In a blow pipe, a tube, means for supplying a mixture of air and fuel to said tube, and a burner carried by said tube and comprising a casing member, a nozzle end therefor having an opening therein of substantially uniform diameter, a transverse wall within the nozzle end and provided with a centrally disposed mixture discharge 90 opening of less diameter than the opening in said nozzle end whereby a suction is created within said nozzle end, and a baffle plate within said casing member of larger diameter than the mixture discharge opening and adjacent thereto. 100

3. A blow pipe, comprising a hollow casing having a mixing chamber for gas and air and a fan chamber communicating therewith, a fan in said fan chamber, a burner member communicating with said fan chamber and supplied with mixture thereby, a conduit for supplying gas to said mixing chamber, adjustable means for admitting to said chamber quantities of air varying from 110 zero to a maximum, said conduit being also provided with a port for preliminarily admitting a small supply of air to the gas current before it reaches the mixing chamber, and means for admitting an additional air 115 supply to the burner member between its outlet and the fan chamber. 120

4. A blow pipe, including a burner tube, a spider held within the end thereof and carrying a circular baffle plate spaced beyond the end of said tube, and a burner casing surrounding the end of said tube and having an enlargement surrounding and extending beyond said plate, said casing having a cross wall beyond said plate and form- 130

ing therewith a restricted passage through which the gas converges to an opening in said wall smaller than said plate.

5. A blow pipe, including a burner tube, 5 a spider held within the end thereof and carrying a circular baffle plate spaced beyond the end of said tube, and a burner casing surrounding the end of said tube and having an enlargement surrounding and extending beyond said plate, said casing having a cross wall beyond said plate and forming therewith a restricted passage through which the gas converges to an opening in said wall smaller than said plate, said casing being adjustable along said tube to more or less restrict said passage.
- 10 6. A blow pipe, including a burner tube, a spider held within the end thereof and carrying a circular baffle plate spaced beyond the end of said tube, and a burner casing surrounding the end of said tube and having an enlargement surrounding and extending beyond said plate, said casing having a cross wall beyond said plate and forming therewith a restricted passage through which the gas converges to an opening in said wall smaller than said plate, said casing being adjustable on said tube to more or less restrict said passage and having an extension beyond said cross wall provided with
- 15 20 25

which the gas converges to an opening in said wall smaller than said plate, said casing having an extension beyond said cross wall provided with lateral air inlet openings.

- 30 7. A blow pipe, including a burner tube, a spider held within the end thereof and carrying a circular baffle plate spaced beyond the end of said tube, and a burner casing surrounding the end of said tube and having an enlargement surrounding and extending beyond said plate, said casing having a cross wall beyond said plate and forming therewith a restricted passage through which the gas converges to an opening in said wall smaller than said plate, said casing being adjustable on said tube to more or less restrict said passage and having an extension beyond said cross wall provided with lateral air inlet openings.
